UNITED STATES PATENT OFFICE.

JOHN ERNEST KENNEDY, OF MONTREAL, CANADA.

DESIGN FOR A COAT-HANGER.

SPECIFICATION forming part of Design No. 29,872, dated December 27, 1898.

Application filed November 17, 1898. Serial No. 696,730. Term of patent 7 years.

To all whom it may concern:

Be it known that I, JOHN ERNEST KENNEDY, a subject of Her Majesty the Queen of Great Britain, residing at Montreal, in the district of Montreal, in the Province of Quebec, Canada, have invented and produced a new and original Design for Coat-Hangers, of which the following is a specification, reference being had to the accompanying drawing, forming part thereof.

The drawing represents a perspective view of the coat-hanger, showing my new design.

As shown in the drawing, the leading or material feature of my design consists of the arched double wire A A, converging toward the center and forming a hook A'. The ends

of the double-wire arc flare outwardly and turn upwardly to form the end arches A². Partially surrounding the hook A', I secure on the converging portion of the double wire 20 the raised arc-shaped bracket or support B. The wires are connected or bound together, as indicated.

Having described my invention, what I claim as new, and desire to secure by Letters 25 Patent, is—

The design for a coat-hanger, as herein shown and described.

JOHN ERNEST KENNEDY.
